DESIGN FOR A PORTABLE ELECTRIC POLISHER

Gustave J. Soderberg, Babylon, N. Y.

Application October 5, 1944, Serial No. 115,632

Term of patent 14 years

(Cl. D9—2)

To all whom it may concern:

Be it known that I, Gustave J. Soderberg, a citizen of the United States, residing in the city of Babylon, county of Suffolk, and State of New York, have invented a new, original, and ornamental Design for a Portable Electric Polisher, of which the following is a specification, reference being had to the accompanying drawings, forming a part thereof.

Figure 1 is a side view of a portable electric polisher, showing my design.

Fig. 2 is a top plan view of the polisher;

Fig. 3 is a rear view thereof.

I claim:

The ornamental design for a portable electric polisher, as shown.

GUSTAVE J. SODERBERG.
